IRONING MACHINE

Wallace F. Oliver, Detroit, Mich., assignor to
Hydraulic Brake Company, Detroit, Mich., a
corporation of California

Application May 11, 1933, Serial No. 670,612

16 Claims. (Cl. 38—25)

This invention relates to ironing machines and more particularly to hydraulically actuated ironing machines.

Broadly the invention comprehends an ironing machine including relatively movable ironing elements and fluid pressure means for moving one of the elements into operative position and for moving the other element to create an ironing pressure between the elements.

10 In the illustrated embodiment of the invention a fluid pressure producing means is connected through expandible means to relatively movable ironing elements, one movable thereby into operative position and the other movable thereby to create an ironing pressure between the elements.

The expandible means is operable at a relatively low pressure for moving one of the elements into operative position, and at a higher predetermined pressure for moving the other ironing element to create an ironing pressure between the elements.

20 A control means is provided for releasing the pressure on both of the expandible elements, also a safety means for releasing the pressure, and automatically operative means for returning the elements to their normal position upon release of pressure.

An object of the invention is to provide a hydraulically actuated ironing machine for home use.

30 Another object of the invention is to provide a hydraulically actuated ironing machine which is entirely automatic in its operation.

Another object of the invention is to provide a hydraulically actuated ironing machine including fluid pressure producing means and expandible means operable thereby, and relatively movable ironing elements actuated by the expandible means, first to move one of the elements into operative position, and then to move the other element to create an ironing pressure between the elements, such movements of the elements being automatic.

Other objects of the invention will appear from the following description taken in connection with the drawings forming a part of this specification, and in which,—

Figure 1 is a side elevation, partly in section and partly broken way, of an ironing machine embodying the invention;

50. Figure 2 is a sectional view substantially on line 2—2, Figure 1;

Figure 3 is a plan view partly in section;

Figure 4 is an enlarged view of one of the cylinders and connections for raising and lowering 55 the head from the buck;

Figure 5 is an enlarged view of one of the cylinders and associated parts for actuating the buck;

Figure 6 is an enlarged top plan view of the control valve;

5

Figure 7 is a side elevation of the control valve;

Figure 8 is an enlarged sectional view of the control valve;

Figure 9 is a sectional view taken substantially on line 9—9, Figure 8;

10

Figure 10 is a sectional view of the gear pump;

Figure 11 is an end elevation of the gear pump, partly broken away and partly in section;

Figure 12 is a fragmentary view of the gear pump;

15

Figure 13 is a fragmentary view illustrating the operating lever and associated parts;

Figure 14 is a diagrammatical view of the fluid pressure system of the ironing machine;

Fig. 15 is a vertical sectional view of the control 20 valves; and

Fig. 16 is a fragmentary view of the operating lever and means for retaining this lever in depressed position.

Referring to the drawings for more specific 25 details of the invention, four corresponding upright members 10 are connected by side members 12 and end members 14 to provide a suitable support for a top 16. The members 12 have bolted or otherwise secured thereto a rectangular frame 30 18 having spaced members 20 extending upward through suitable openings in the top 16. The members 20 have bifurcated ends 22 in which are pivoted corresponding arms 24 to which is pivotally connected a head 26 adaptable for cooperation with a buck 28.

The arms 24 are connected by springs 30 to brackets 32 secured on the back of the members 20. These springs urge the arms 24 upward to raise the head from the buck. The springs 30 40 may be rendered ineffective when the machine is not in use by adjusting a thumb screw mounted in one of the members 20 to engage a lug 36 formed on one of the arms 24.

The buck 28 is movable in a perpendicular 45 plane through a suitable opening in the top 16. The base of the buck has suitably secured thereto pins 38 and 40 extending downward through openings in the frame 18, and sleeved on the pins between the base of the buck and shoulders 50 formed in the openings in the frame are springs 42, for yieldingly supporting the buck.

The frame 18 has journaled thereon a transverse shaft 44, and keyed to the respective ends of the shaft are bell crank levers 46 each having 55

a short arm and a long arm. The long arms of the bell crank levers are connected by links 48 to the arms 24, the links 48 being of such structure as to house the springs 30. The short arms of the bell crank levers 46 are connected by toggles 50 to stub shafts 52 journaled in the frame 18. Each of the toggles 50 has a long leg and a short leg. The long legs of the toggles are pivoted to bell crank levers 46 and the short legs of the toggles are keyed to the stub shafts 52. The knees of the toggles engage compression members, preferably springs 54, when the toggle is extended, that is, when the head 26 is in engagement with the buck 28, and tension members, preferably springs 56, connect the stub shafts to the pivots connecting the long legs of the toggles to the short arms of the bell crank levers 46. The springs 54 serve to trip the toggle, and the springs 56 actuate the toggles to raise the head from the buck, this movement of the head being augmented by the springs 30. The stub shafts have keyed thereon arms 58 to which are pivotally connected rods 60 and 62, the object of which will hereinafter appear.

25 The actuating means include a suitable motor 64 supported by a stirrup suspended from the side member 12. The motor is suitably connected to a pump unit 66, also supported by the stirrup, and a drip pan 68 is supported by the side member 12 beneath the stirrup.

30 The pump includes a casing 70 providing a fluid reservoir 72 opened at its top. The casing has a cover plate 74, and is further provided with a filling opening closed as by a plug 76 and a drain opening closed by a plug 78. A transverse boss 80 connects opposite walls of the casing near the top thereof. This boss is bored to provide a pump chamber 82, a bearing 84 adjacent thereto, and a packing chamber 86 for the bearing. The 35 packing chamber is transversely bored at 88, the object of which will hereinafter appear. An inlet passage 90 extends from the bottom of the reservoir to the pump chamber 82 and an outlet passage 92 extends from the pump chamber to 40 outlet passages 94 and 96, one of which, the outlet 96, is controlled by a spring-pressed valve 98.

45 A shaft 100 supported for rotation by the bearing 84 extends through the packing chamber 86, and a packing nut 102 sleeved on the shaft and 50 threaded in the packing chamber retains a packing unit against displacement. This packing unit preferably includes spaced quantities of packing material 104 and 106 having interposed retainers 108 and 110, and a coil spring 112 between the retainers bridges the transverse passage 88, so that oil seeping past the packing 55 104 may freely return to the reservoir. This structure has a decided advantage in that there may be a very high pressure imposed on the 60 packing 104, whereas only atmospheric pressure is on the packing 106.

65 The shaft 100 has formed thereon a crown gear 114 fitted closely in the pump cylinder 82, and a cover plate 116 for the open end of the pump chamber has a part extending into the chamber. The cover plate supports a stub shaft 118 on which is rotatably mounted a gear 120 in mesh with the crown gear 114. The shaft 100 is connected to the armature shaft of the motor 70 64 and is driven thereby to rotate the gears 114 and 120 in clockwise direction. As shown in Figure 11, the gears lift the fluid or liquid from the reservoir 72 through the intake passage 90 into the pump chamber 82 and discharge the 75 fluid or liquid from the pump chamber through

the outlet passage 92 communicating with the outlet passages 94 and 96.

5 The outlet 94 of the pump is connected by a conduit 122 to an expandable means including a cylinder 124, which in turn is connected by a conduit 126 to another expandable means including a cylinder 128. The cylinders are suitably secured to the frame 18 and pistons 130 movable in the cylinders have leak-proof cups on their heads and recesses in the backs thereof for 10 the reception of the pins 60 and 62 through which the arms 56 may be rocked to actuate the toggles 50 and, through the connections thereto, the head 26.

15 The outlet 96 is connected by a conduit 132 to an expandable means including a cylinder 134, which in turn is connected by a conduit 136 to another expandable means including a cylinder 138. The cylinders 134 and 138 have movable therein pistons 140 provided with leak-proof cups 20 142 held in position by coil springs interposed between the cups and the heads of the cylinders. The pistons have case-hardened inserts 144 for the reception of the pins 38 and 40 on the buck 28, through which the buck may be raised and 25 lowered. The cylinder 128 is connected by a conduit 146 to a control valve housing 148, the cylinder 138 is connected by a conduit 150 to the control valve housing 148, and a conduit 152 connects the control valve housing 148 to the 30 reservoir 72.

35 The control valve housing 148 includes a casting having a flange by which the casting may be attached to the frame 18. The casting has parallel cylinders 154 and 156 and spring-pressed valves 158 and 160 arranged concentrically to the cylinders. The valve 158 controls a passage 162 communicating with the conduit 146 leading from the cylinder 128, and the valve 160 controls a passage 164 communicating with the conduit 40 150 leading from the cylinder 138. The cylinders 154 and 156 have ports 166 and 168 communicating with a passage 170 connected to the conduit 152 leading to the reservoir 72. The passage 164 has a branch passage 172 communicating with passage 170 and controlled by a 45 spring-pressed valve 174.

50 The cylinders 154 and 156 have movable therein pistons 176 and 178. The heads of the pistons have thereon leak-proof cups 180 and plungers 55 182 adapted to trip the valves 158 and 160. The plungers have secured thereon collars 184 and springs interposed between the collar and the heads of the cylinders serve to return the pistons. The pistons are actuated by a lever 186 pivoted 55 on the frame as at 188 and held in engagement with the pistons by a spring 190. The lever may be held in a depressed position by suitable means 192 attached to one of the uprights 10.

60 In operation, the head 26 is generally held in lowered position by a thumb screw 34 engaging a lug 36 on one of the arms 24 supporting the head 26. By adjusting the thumb screw 34 to disengage the lug, the head is automatically raised from the buck, as will hereinafter be explained. 65 The article to be ironed is then placed on the buck. The control valves are normally open. Accordingly, upon starting the motor 64 the pump 66 is actuated to deliver fluid from the reservoir 72 through the intake passage 90, the pump 70 chamber 82, and the outlet passage. The fluid circulates from the pump through branch passage 94, the conduit 122, to the cylinder 124, through this cylinder and the conduit 126 to cylinder 128, through cylinder 128 and conduit 146 to the con- 75

tral valve housing 148, through the control valve housing 148 and the conduit 152 back to the reservoir. During this circulation of the fluid no operation of the apparatus takes place.

5. Now, upon actuating the operating lever 186 to close the control valves 158 and 160, the pump continues to deliver fluid as above described up to the control valve housing 148, where the flow of the fluid is checked by valve 158. The fluid 10 pressure in the cylinders 124 and 128 causes movement of the pistons therein resulting in movement of the rods 60 and 62 to rock the levers 58 keyed to the stub shafts 52, and thereby rotate the shafts 52. This rotation of the shafts 15 52 results in straightening the toggles 50. When the toggles are straightened they snap across the center to engage the compression springs 54.

The toggles 50 have long and short legs. The short legs of the toggles are keyed to the shafts 52 20 and the long legs of the toggles are pivoted to the short arms of the bell crank levers 46, the long arms of which are pivoted to links 48 which in turn are pivoted to the arms 24 supporting the head 26. Hence, in straightening the toggles the bell crank levers are moved through an angle and this movement is transmitted through the links 25 48 to the arms 24 resulting in lowering the head 26 into operative position.

After the head has been moved to operative position, the pressure builds up to a predetermined 30 pressure, and trips the valve 98. The fluid now circulates through outlet 92 of the pump, branch outlet 96, and conduit 132 to cylinder 134, through this cylinder and conduit 136 to cylinder 138, 35 through this cylinder and conduit 150 to control valve housing 148, where the flow of the fluid is checked by the valve 160. The pressure in the cylinders 134 and 138 causes movement of the pistons 140 resulting in moving the buck 28 to engage the head with sufficient pressure between 40 them to effectively iron the work. The pressure continues to build up. However, should the pressure become too great, the safety valve 174 is actuated at a predetermined pressure to return 45 the fluid through the control valve housing 148 and conduit 152 to the reservoir.

Upon accomplishing the work, the operating lever 186 is released, whereupon the control valves 50 are opened and the fluid circulates as before. As soon as the control valves are open, the compression spring 54 moves the knee of the toggle past center, whereupon springs 56 become effective to 55 actuate the toggles 50. This movement of the toggles moves the bell crank levers 46 through an angle and thereby imposes a pull through links 48 on arms 24. This pull on the arms 24 is augmented by the tension springs 30 connected between the arms 24 and the uprights 20, and results in raising the head 26 clear of the buck 28, 60 the action being entirely automatic.

Although this invention has been described in connection with certain specific embodiments, the principles involved are susceptible of numerous other applications that will readily occur to 65 persons skilled in the art. The invention is, therefore, to be limited only as indicated by the scope of the appended claims.

Having thus described the various features of the invention, what I claim as new and desire to 70 secure by Letters Patent is:—

1. An ironing machine comprising a pair of ironing elements, an expansible means for moving one of the elements into operative position, expansible means for moving the other element to 75 create an ironing pressure between the elements,

means for supplying fluid under pressure to the expansible means and means operable only at a predetermined pressure to admit the fluid to the expansible means for actuating one of the elements.

2. An ironing machine comprising a head, a buck for cooperation therewith, expansible means for moving the head into operative position, expansible means for moving the buck to create an ironing pressure between the head and buck compression means for supplying fluid under pressure to the expansible means and means admitting the fluid to the expansible means for actuating the buck only at a predetermined pressure in the expansible means for actuating the head. 15

3. An ironing machine comprising a head, a buck for cooperation therewith, expansible means for moving the head into operative position, expansible means for moving the buck to create an ironing pressure between the head and the buck, pressure producing means for supplying fluid under pressure to the expansible means, and fluid actuated means connected to the pressure producing means for controlling admission 20 of fluid to the expansible means for sequential 25 operation.

4. An ironing machine comprising a pair of ironing elements, expansible means for moving one of the elements into operative position, expansible means for moving the other element to create an ironing pressure between the elements, compression means for supplying fluid under pressure to the respective expansible means, means controlling the flow of fluid through the respective expansible means, and means connected between the compression means and the last-mentioned expansible means and operable at a predetermined pressure to admit the fluid to the last-mentioned expansible means. 30 35

5. An ironing machine comprising a pair of ironing elements, expansible means for moving one of the elements into operative position, expansible means for moving the other element to create an ironing pressure between the elements, compression means for supplying fluid under pressure to the respective expansible means, control means for checking the flow of fluid through the respective expansible means, means between the respective expansible means and the compression means operable at a predetermined pressure to admit fluid to the expansible means for actuating one of the elements, means to relieve pressure on the expansible means, and automatically operable means for returning the ironing elements to normal position upon release of pressure on the expansible means. 40 45 50 55

6. An ironing machine comprising a head and a buck, an expansible element for moving the head into operative position, an expansible element for moving the buck against the head to create an ironing pressure, compression means for supplying fluid under pressure to the expansible elements, control means for checking the flow of fluid through the expansible elements, a pressure actuated valve operable at a predetermined pressure to admit the fluid to the expansible element for actuating the buck, a valve for relieving pressure in the expansible elements, and automatically operated means for returning the head to its normal position. 60 65 70

7. An ironing machine comprising a head and a buck, a pair of expansible elements for moving the head into operative position, a pair of expansible elements for moving the buck to create an ironing pressure between the head and buck, 75

- compression means for supplying fluid under pressure to both pairs of expansible elements, control valves for checking the flow of fluid through both pairs of expansible elements, a fluid pressure actuated valve operable at a predetermined pressure to admit fluid to one pair of the expansible elements, a valve for relieving pressure in the expansible elements, and spring actuated means for returning the head to its normal position upon release of pressure on the expansible elements.
8. An ironing machine comprising a motor, a pump operated thereby, a fluid reservoir for the pump, an expansible element connected to the pump, a second expansible element connected to the pump, a pair of cooperating ironing elements actuated respectively by the respective expansible elements, a pressure actuated valve connected between the second expansible element and the pump, and control valves for checking the flow of the fluid from the expansible elements back to the reservoir.
9. An ironing machine comprising a motor, a pump operated thereby, a fluid reservoir for the pump, a pair of expansible elements connected to the pump, a second pair of expansible elements connected to pump, cooperative ironing elements operated respectively by the respective pairs of expansible elements, a pressure actuated valve connected between the second pair of expansible elements and the pump, and control valves connected between the respective pairs of expansible elements and the reservoir for checking the flow of the fluid from the respective pairs of expansible elements back to the reservoir.
10. An ironing machine comprising a motor, a pump operated thereby, two pairs of expansible elements connected to the pump, a pressure actuated valve connected between one pair of expansible elements and the pump, valves controlling the flow of fluid, cooperative ironing elements operated respectively by the respective pairs of expansible elements, and spring-actuated means for returning one of the ironing elements to its normal position upon release of pressure in the expansible elements.
11. An ironing machine comprising a frame having spaced uprights, a buck supported on the frame, arms pivoted to the uprights, a head supported by the arms for cooperation with the buck, tension members connecting the arms to the uprights, toggles on the frame, means for actuating the toggles, bell crank levers pivoted to the toggles, and links connecting the bell crank levers to the arms supporting the head.
12. An ironing machine comprising a frame having spaced uprights, a buck supported on the frame, arms pivoted to the uprights, a head pivoted to the arms for cooperation with the buck, tension members connecting the arms to the uprights, bell crank levers pivoted on the frame, links connecting the bell crank levers to the arms, toggles connected to the bell crank levers, and means for actuating the toggles including springs connecting their respective ends.
13. An ironing machine comprising a frame having spaced uprights, a buck resiliently supported on the frame, arms pivoted to the uprights, a head supported by the arms for cooperation with the buck, tension members connecting the arms to the uprights, a transverse shaft journaled on the frame, bell crank levers keyed to the shaft, links connecting the bell crank levers to the arms, stub shafts journaled on the frame, toggles connecting the stub shafts to the bell crank lever, means for rocking the stub shafts, and springs connecting the respective ends of the toggle.
14. An ironing machine comprising a frame having spaced uprights, a buck resiliently supported on the frame, arms pivoted to the uprights, a head pivoted to the arms for cooperation with the buck, tension members connecting the arms to the uprights, a shaft journaled on the frame, bell crank levers keyed to the shaft, links connecting the bell crank levers to the arms, stub shafts journaled on the frame, toggles connecting the stub shafts to the bell crank levers, springs connecting the respective ends of the toggles, and force applying means connected to the stub shafts for actuating the toggles.
15. An ironing machine comprising a frame, a buck resiliently supported on the frame, arms pivoted to the frame, a head supported by the arms for cooperation with the buck, tension members connecting the arms to the frame, a shaft journaled on the frame, bell crank levers on the shaft, links connecting the bell crank levers to the arms, stub shafts journaled on the frame, toggles connecting the stub shafts to the levers, springs connected between the respective ends of the toggles, fluid pressure means including expansible means for rocking the stub shafts to move the head into operative position, expansible means for moving the buck to create an ironing pressure between the head and the buck, and a compression means for supplying fluid under pressure to the expansible means.
16. An ironing machine comprising a frame, a buck resiliently supported thereon, arms pivoted to the frame, a head supported by the arms for cooperation with the buck, tension members connecting the arms to the frame to raise the head, a shaft journaled on the frame, bell crank levers keyed to the shaft, links connecting the levers to the arms, said links housing the tension members, stub shafts journaled on the frame, toggles keyed to the shafts and pivotally connected to the levers, compression members receiving the knees of the toggles, a pair of expansible elements for actuating the toggles to move the head into operative position, another pair of expansible elements for moving the buck against the head to create an ironing pressure, means for supplying fluid under pressure to the expansible elements, and valves for controlling the flow of fluid through the expansible elements.
